SUPPORTING APPARATUS

Carl E. Holm, Berwyn, Ill., assignor to Victor E. Kossian, Berwyn, Ill.

Application November 18, 1947, Serial No. 786,639

3 Claims. (Cl. 248—163)

1

This invention relates to supporting apparatus. More particularly, this invention relates to supporting apparatus which may be adapted for use in and as an interior or exterior scaffold by painters, decorators and like workmen, and the like, and for use, in one form thereof, as a step ladder.

An object of the present invention is to provide a new and improved supporting apparatus of the character hereinafter described and which may be readily adjusted for use in and as an interior or exterior supporting scaffold for use by painters, decorators, and the like, and for use, in one form thereof, as a step ladder.

An additional object of the invention is to provide in the new supporting apparatus a novel supporting unit which may be readily adjusted for and adapted to the various uses thereof as hereinafter indicated.

Another object of the invention is to provide in the new supporting apparatus a novel means for enabling a lower end portion of the new supporting means to yieldably grip a horizontal supporting surface on which the new supporting apparatus may be rested.

A further object of the invention is to provide in the new supporting apparatus a novel means for enabling the upper and generally horizontally extending supporting arms of the main supporting unit which is embodied in the new supporting apparatus to grip a vertically extending supporting surface, such as interior or exterior wall, against which the new supporting apparatus may be rested.

Other and further objects of the present invention will be apparent from the following description and claims and are illustrated in the accompanying drawings which, by way of illustration, show preferred embodiments and principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a side elevational view illustrating one form of the new supporting apparatus as adapted for use as an interior or exterior scaffold support for use by painters, decorators, and like workmen, or for use by home owners desiring to do this type of work;

Fig. 2 is a top plan view of the form of the supporting apparatus shown in Fig. 1;

Fig. 3 is a fragmentary detail view illustrating parts of the apparatus embodied in the form of the new scaffold supporting apparatus illustrated in Fig. 1;

Fig. 4 is a fragmentary view partly in section and partly in elevation, illustrating the lower end portion and supporting foot or caster therefor embodied in the form of the invention illustrated in Fig. 1;

Fig. 5 is a fragmentary sectional view illustrating a preferred form of one of the yieldable supporting feet or caster units which are embodied in the new supporting apparatus for yieldably gripping a horizontal supporting surface on which the supporting apparatus shown in Fig. 1 may be rested;

Fig. 6 is an elevational view illustrating another form of the invention adapted for use as a household ladder;

Fig. 7 is an end elevational view as seen from the left in Fig. 6;

Fig. 8 is a fragmentary view illustrating a part of the form of the invention illustrated in Figs. 6 and 7;

Fig. 9 is a sectional plan view on line 9—9 in Fig. 8; and

Fig. 10 is a transverse sectional view on line 10—10 in Fig. 8.

A typical embodiment of the present invention is illustrated in Figs. 1 to 5, inclusive, and comprises a scaffold support, generally indicated at 25, and which includes a supporting unit 26 on which one end of a plank 27 is mounted, Fig. 1. It will be understood that the other end of the plank will be supported on another supporting unit, not shown, identical to the supporting unit 26, to thereby provide a support for a painter, decorator, or the like, who might wish to work upon a vertical wall surface, as 53.

The supporting unit 26 comprises an upwardly extending main and lower body portion 28 and a generally horizontally extending upper portion 29. Each of the upwardly extending main body portions 28 includes a pair of tubular metal legs 30 which may be made of any suitable light metal such as an aluminum alloy, interconnected by a series of vertically spaced braces or rungs 31 integrally connected thereto in any suitable manner, as by welding. Each of the lower and main body portions 28 also includes a lower supporting leg portion 32, which may be made of any suitable type of solid or tubular metal, and each of these lower supporting leg portions 32 is telescopically inserted into the corresponding one of the upper leg sections 30.

A collar 33 is welded to the lower end portion

of each of the upper tubular leg sections 30 and a manually operable set screw 34 is adjustably mounted in each of the collars 33 so that its inner end portion may bear against the lower end portion of each of the upper leg sections 30 and thus hold the two telescopically interconnected leg sections 30 and 32 in the desired adjusted position relative to each other and at the desired effective height.

As shown in Fig. 5, each of the lower and inner leg sections 32 has a caster unit 35 attached thereto and each of these caster units 35 includes a rubber or like yieldable gripping member 36 having a socket 37 formed in its upper surface. A resilient pad 38 is mounted in the socket 37 and a hemispherical metal rest 39 is attached to and anchored in the rubber insert 38. The lower end or bottom edge 40a of the lower and inner leg member 32 rests upon the upper surface of the hemispherical metal member 39.

A yieldable metallic attaching member 40 has its lower end portion 41 anchored in the resilient or rubber member 38 and this attaching member 40a includes a pair of resilient or spring jaws 42 which extend upwardly into a socket 43 which is provided in the lower end portion of each lower leg section 32, Fig. 5.

The generally horizontal upper section 29 of each of the supporting units 26 includes a pair of converging arms 44 which are formed as integral extensions of the leg sections 39 and a tubular metal sleeve 45 is welded between these upper tubular arms 44, Fig. 2. The upper section 29 of each supporting unit 26 also includes a tubular member 46 which is telescopically inserted into the tubular sleeve 45. Each of the tubular arms 46 or sections 46 has a yieldable gripping unit 47 attached thereto, at the outer end thereof in a manner which will be discussed in greater detail hereinafter. Each of these gripping units 47 comprises a body or block 69 of yieldable material, such as rubber, at which a threaded stud 50 is attached.

The inner end portion of each tubular section 46 is engaged with a stop pin or abutment 51, carried by the tubular sleeve 45. As shown in Fig. 1, the pin 51 extends upwardly above the tubular sleeve 45 and provides a stop for holding the plank or like support against lateral shifting movement when the new scaffold supporting apparatus is in assembled position.

A brace 54 extends between each of the upper leg sections and the tubular sleeve 45 and its end portions are welded thereto.

When the new scaffold supporting apparatus shown in Figs. 1 to 5, inclusive, is in use the lower end edges 40 of the lower leg sections 32 have a limited rocking movement upon the upper surfaces of the hemispherical metal members 39, the caster units 35 being of the rocking or ball and socket type, so as to enable the new scaffold supporting apparatus to be accommodated to irregularities in the horizontal surface in which it is arranged.

The caster units 35 may be detached from the lower leg sections 32 by pulling downwardly thereon so as to urge the yieldable spring jaws 42 together whereupon the spring jaws 42 may be slipped out of the socket 43 which is arranged in the lower end portion of each lower leg section 32 (Fig. 5).

The invention illustrated in Figs. 1 to 5, inclusive, includes an additional and auxiliary vertically extending supporting unit, which is generally indicated at 55, and one of which is

associated with each of the main supporting units 26.

The auxiliary supporting unit 55 includes a vertically extending tubular upper metal section 56 having a collar 57 secured to the lower end portion thereof. The additional and auxiliary supporting unit 55 also includes a lower rod-like metal section 58 which is telescopically inserted into the corresponding tubular upper metal section 56, and a manually operable set screw 59 is mounted in the collar 57 so as to clamp the upper and lower leg sections 56 and 58 together at the desired adjusted vertical height.

A resilient gripping foot for caster 60 is attached to the lower and inner leg member 58 by means of a threaded stud 61 which is threaded into a threaded socket 62 formed in the lower end portion of the lower and inner leg member 58.

The auxiliary supporting unit 55, which is embodied in the form of the invention shown in Figs. 1 to 5, inclusive, comprises a T-shaped connecting unit, which is generally indicated at 63, and which includes a horizontally extending arm 64 having an end portion of the tubular arm 46 detachably connected thereto, as by a pin 65, a vertically extending depending arm 66 having the upper end portion of the upper tubular leg section 56 detachably attached thereto, as by a manually operable set screw 57, and a second horizontally extending internally threaded arm 68 to which the body 69 of the resilient gripping unit 47 is detachably attached by the threaded stud or shank 50, (Fig. 3).

The use and operation of the form of the invention shown in Figs. 1 to 5, inclusive, are as follows: The lower leg sections 58 of the auxiliary supporting unit 55 may be inserted in the tubular upper leg sections 56 and adjusted to the desired height by means of the set screws 59. Similarly, the lower leg sections 32 of each of the main supporting units 26 may be inserted into one of the upper tubular leg sections 30 and adjusted to the desired height by means of one of the set screws 34. The T connecting unit 63 may be attached to the end portions of the parts 46 and 56 and clamped thereto by means of the set screws 65 and 67, and the gripping unit 47 threaded into the horizontally extending arm 68 of the T connection 63. The supporting apparatus thus assembled may then be arranged in upright position, adjacent a vertical wall surface 53, with the bodies 69 of the yieldable gripping units 47a gripping the vertical wall surface 53a. A suitable horizontal support 27, Fig. 1, may then be laid across the horizontally extending arms 46 in abutting relationship with the upwardly extending pins 51 whereupon the new scaffold supporting apparatus, shown in Figs. 1 to 5, inclusive, will provide an effective scaffold support for interior or exterior use by painters, and decorators, or for other uses. During such usage the auxiliary supporting units 55 provide additional support for a horizontal plank and the workman or workmen thereon, over and above the support provided by the supporting units 26.

A modified form of the invention is illustrated in Figs. 6 to 10, inclusive, and those parts thereof which are similar to corresponding parts shown in any of Figs. 1 to 5, inclusive, and which have been previously described have been given the same reference numerals followed by the additional and distinguished reference character "d."

The form of the invention shown in Figs. 6 to 10, inclusive, differs from the other forms of the

invention, previously described, in that it is especially adapted for use as a household or step ladder.

The form of the invention shown in Figs. 6 to 10, inclusive, includes a supporting leg unit 79 which includes a generally vertically extending tubular metal leg 80 having an offset portion 81 between its upper and lower ends so as to provide for additional stability in the step ladder thus formed.

The upper end portion 82 of the supporting leg 80 has a pin 83 extending downwardly thereinto and this pin 83 and the upper end portion of this pin 83 extends into a recess or socket 84 provided in a supporting member which is in the form of a substantially square platform 27d which is mounted upon the upper end portions 44d of the supporting unit 26d. The pin 83 is attached to the supporting member or platform 27d by a fastening element in the form of a screw 85 which is countersunk in the platform 27d as shown in Fig. 8.

The upper end portion 82 of the supporting leg 80 has a laterally extending arm 86 which projects into the sleeve 45d which is arranged between and is welded to, the adjacent but spaced arms 44d which are employed in the upper end portion 29d of the supporting units 26d. The tubular arm 86 has a bayonet slot 87 formed therein and this bayonet slot 87 is engageable with a stop pin or abutment 51d which is anchored in the tubular sleeve 45d and has its upper end portion projecting into an opening 88 in the platform 27d, as shown in Figs. 9 and 10.

The vertically extending supporting leg 80 has a bifurcated lower end portion 89 which provides a pair of spaced vertically extending tubular legs 90 and each of the lower leg portions 58a is adapted to extend into the lower end portion of one of the tubular legs 90 and to be releasably and adjustably clamped thereto by a set screw 59d mounted in a collar 57d which is mounted on the lower end portion of each of the tubular legs 90. A gripping unit or caster 60d, similar to the casters unit 60—61—62, as shown in Fig. 3, may be mounted upon the lower end portion of each of the lower leg sections of 58d which are embodied in the supporting unit 79, as shown in Figs. 6 to 10, inclusive.

In the use of the form of the invention shown in Figs. 6 to 10, inclusive, the main supporting unit 26d may be arranged in spaced but coextensive relationship so that the supporting member or platform 27d may be extended between and rested upon the tubular sleeves 45d.

The lower leg sections 58d may be inserted into the tubular lower leg sections 90 of the supporting unit 79 and clamped thereto, at the proper adjusted height, by means of the set screws 59d, whereupon the tubular arm 86 of the supporting unit 79 may be connected to the main supporting unit 26d at the connection between the pin 51d and bayonet slot 87, Fig. 9.

The assembly of the parts embodied in the form of the invention illustrated in Figs. 6 to 10, inclusive, may then be completed by attaching the pin 83 to the platform 27d, by means of the screw 85, and then lowering the platform 27d into position upon the tubular sleeves 45d so that the pin 51d enters into the opening 88 in the supporting member or platform 27d.

When the form of the invention illustrated in Figs. 6 to 10, inclusive, is thus assembled it provides a simple and inexpensive household step

ladder which may be used in a room of a residence or other building, and in like places, wherever a step ladder may be used.

It will also be noted, in this connection, that when the form of the invention illustrated in Figs. 6 to 10, inclusive, is thus assembled the horizontal rungs 31d of the main supporting unit 26d provide steps by means of which the user of the supporting apparatus may climb up to and down from the horizontal supporting member or platform 27d.

It will thus be seen from the foregoing description considered in conjunction with the accompanying drawings, that the present invention has the desirable advantages and characteristics, and accomplishes its intended objects, including those hereinbefore pointed out and others which are inherent in the invention.

I claim:

20. A supporting unit comprising a pair of spaced tubular upright leg members having formed integral therewith generally horizontally extending and converging tubular metal upper end portions, a generally horizontally extending tubular metal sleeve arranged between and attached to said generally horizontally extending and converging tubular upper end portions of said leg members in substantially parallel extending relation thereto for detachably supporting a generally horizontally extending supporting element therein, and an auxiliary vertically extending supporting member including a substantially vertically extending supporting leg member projecting below said sleeve, said auxiliary supporting member including connecting means for detachably connecting said substantially vertically extending supporting leg member to said tubular sleeve.

40. A supporting unit comprising a pair of spaced tubular upright leg members having formed integral therewith generally horizontally extending and converging tubular metal upper end portions, a generally horizontally extending tubular metal sleeve arranged between and attached to said generally horizontally extending and converging tubular upper end portions of said leg members in substantially parallel extending relation thereto for detachably supporting a generally horizontally extending supporting element therein, and an auxiliary vertically extending supporting member including a substantially vertically extending supporting leg member projecting below said sleeve, said auxiliary supporting member including connecting means for detachably connecting said substantially vertically extending supporting leg member to said tubular sleeve, said auxiliary supporting member including a resilient gripping member attached to and carried by said connecting means for yieldably gripping a vertically extending wall surface.

60. A supporting unit comprising a pair of spaced tubular upright leg members having formed integral therewith generally horizontally extending and converging tubular metal upper end portions, and a generally horizontally extending tubular metal sleeve arranged between and attached to said generally horizontally extending and converging tubular upper end portions of said leg members in substantially parallel extending relation thereto for detachably supporting a generally horizontally extending supporting element therein, and an auxiliary vertically extending supporting member including a substantially vertically extending supporting leg member projecting below said sleeve, said auxiliary supporting

member including a generally T-shaped connection for detachably connecting said substantially vertically extending supporting leg member to said tubular sleeve, said auxiliary supporting member including a resilient gripping member attached to and carried by said generally T-shaped connection for yieldably gripping a vertically extending wall surface.

CARL E. HOLM.
